GEO. E. THACKRAY.
ATTORNEY

UNITED STATES PATENT OFFICE.

EMIL C. DANNER, OF WESTMONT BOROUGH, PENNSYLVANIA.

RAIL-ANCHOR AND MANUFACTURE THEREOF.

1,307,084.

Specification of Letters Patent. Patented June 17, 1919.

Application filed April 8, 1919. Serial No. 288,645.

To all whom it may concern:

Be it known that I, EMIL C. DANNER, a citizen of the United States, residing in the borough of Westmont, in the county of Cambria and State of Pennsylvania, (whose post-office address is Johnstown, Pennsylvania,) have invented certain new and useful Improvements in Rail-Anchors and Manufacture Thereof; and I do hereby declare the following to be a clear and exact description, such as will enable others skilled in the art to which it appertains to make and use the same.

My invention relates to improvements in the form and construction and manufacture of rail anchors of the kind which are adapted to be clamped upon a rail flange by the spring pressure of the rail anchor itself, causing certain parts of said anchor to be elastically bent to a greater or less degree to produce a powerful clamping action on the rail flange to prevent the displacement of said anchor thereon.

My rail anchor is formed of a bar of steel, preferably of hard or spring steel, the ends of which are bent over toward each other forming clamping jaws and the intermediate portion of which is bent toward the space between said jaws, the whole being constructed in such a way that when the anchor is inserted below the rail and its longer end placed over one side of the rail flange this allows the shorter end to clear the edge of the opposite rail flange, whereupon the other end of the anchor having the shorter bent end portion is moved upwardly so that the lower surface of the shorter bent end contacts with the upper surface of said rail flange adjacent thereto and the anchor is driven thereon with considerable force, thereby clamping it finally in position. In order to insure that the elastic clamping action will be sufficient, my rail anchor is formed in such a way that the distance between the inner surfaces of the bent-over ends of the rail anchor and the upwardly projecting intermediate portion of the same is less than the corresponding dimensions of the rail flanges, thereby causing the rail anchor to be distorted or elastically sprung in such a way that it exerts a powerful resilient spring pressure on the rail flanges, thereby holding the rail anchor very firmly thereon. As, however, the bent portions of said rail anchor are subjected to severe bending stresses I, therefore, in order to econ-

imize material and to make a much more efficient anchor which is both stiffer and stronger at less weight and expense, make the rail anchor deeper at those portions which are subjected to the greatest concentrations of cross-bending stresses. In order to accomplish this practically I take a bar of steel which may be approximately square, rectangular or of other suitable section, and in the rolling mill I form protuberances at predetermined locations thereon which protuberances may be of the same width as or somewhat narrower than the bar, thus causing a deepening of the same at intervals preferably, though not necessarily in one direction. I locate these deeper portions at such intervals along the length of the bar that when the bar is cut into lengths for forming into rail anchors, the deeper portions will come at the end curves and at the intermediate bent portion in such a way as to strengthen and stiffen those parts which are subjected to the greatest cross bending stresses, due to the elastic distortion in spring clamping the anchor upon the rail flanges.

Having thus given a general description of my invention, I will now, in order to make the matter more clear, refer to the annexed sheet of drawings, which forms part of this specification and in which like characters denote like parts:

Figure 1 is a side elevation of a portion of railway track with my improved rail anchors attached to the rails illustrating the application of my invention. Fig. 2 is a vertical transverse sectional elevation taken on the line II—II of Fig. 1. Fig. 3 is a top plan view of a rolled or forged bar from which my rail anchors are made. Fig. 4 is a transverse section of the bar taken on the line IV—IV of Fig. 3. Fig. 5 is a transverse section of the bar taken on the line V—V of Fig. 3. Fig. 6 is a cross section of a bar through the protuberance which is of substantially the same width as the bar.

Referring now to the numbers of reference on the drawings:—1 indicates the rail in general, 2 are the rail base flanges, 3 are the railway ties against which the anchors abut to prevent creeping of the rails and 4 are the spikes which partially secure the rail on the ties. 5 represents generally the bar from which my rail anchors are made, this being illustrated as of substantially

square section with slightly rounded corners or it may be rectangular, round, or any other suitable section as will be readily understood.

- 5 At intervals prior to cutting the bars in lengths from which to form rail anchors, the bar is provided with integral protuberances 9 and 10 which may be formed in the rolling mill, or by forging, hammering or otherwise, these protuberances causing the bar to be deeper where they occur and if they are formed from the metal of the bar the body of which is of finished size, they are preferably thinner than the bar itself, 15 but I can, if desired, make them as thick or almost as thick as the body of the finished bar, by using a larger section of bar from which to form the smaller sections, as illustrated in Fig. 6, with protuberances. These 20 protuberances 9 and 10 are preferably of curved outline as shown, and merge gradually into the body of the bar, as illustrated. My rail anchor is indicated generally as 6, while 7 is the shorter bent-over end of 25 the same, 8 is the longer bent-over end of the same, thus forming clamping jaws, and 9 is the deeper intermediate, preferably curved portion and 10 are the deeper end portions forming parts of the end bends 30 thereof. As illustrated in Fig. 3, 11 indicates the lines on which the bar is cut to form one anchor, the length between these lines 11, including two protuberances or enlargements 10, adapted to form the deeper 35 curved end portions of my rail anchor and 9 forms the intermediate, deeper stiffener of the anchor. The intermediate portion of the anchor is indicated as 12 and the anchor is so formed that normally this part 12 is 40 so located that it has to be bent downwardly, and away from the ends 7 and 8 to a proper amount when the anchor is secured in place, thus providing a spring clamping action to secure the anchor firmly on the rail flanges 45 in order that it may function properly to prevent the rail from creeping longitudinally of the track by abutting against the rail tie as illustrated in Fig. 1.

As illustrated in Fig. 6, the bar 5 is 50 provided with a protuberance 13, substantially of the same width as the bar as shown in Figs. 1 and 2; the ties 3 are embedded in ballast 14 which prevents them from moving and this in connection with the rail anchor prevents creeping of the rails.

My rail anchor is placed in position by inserting it under the rail and slipping the longer end 8 over the rail flange toward the rail web, whereupon the shorter end 7 can be swung upwardly so as to clear the edge of the opposite flange, after which the shorter end 7 is driven forcibly upwardly on the opposite rail flange and springs or elastically bends the anchor by reason of 65 the contact of the intermediate portion 12

with the lower portion of the rail base, this springing being facilitated by the angle or slope of the upper surface of the flange, thus causing a wedging action as the shorter end is driven on the flange.

70

Although I have described and illustrated my invention in considerable detail, I do not wish to be limited to the exact and specific details thereof as shown and described, but may use such modifications in, 75 substitutions for, or equivalents thereof, as are embraced within the scope of my invention, or as pointed out in the claims.

Having thus described my invention, what I claim and desire to secure by Letters Pat- 80 ent is:—

1. In a rail anchor of the character de- 85 scribed, an intermediate portion adapted to bear against the lower surface of the rail base, a longer and a shorter end portion bent over and adapted to contact with the upper surfaces of the rail flanges, one or more of the bent portions of said rail anchor being stiffened by an integral deepening thereof.

2. A rail anchor comprising a bent bar, 90 the intermediate portion of which is formed to contact with the lower surface of the rail flange, the end portion being adapted to contact with the upper surfaces of the rail flanges, the distance between the gripping surfaces of the end portions and the bearing surface of the intermediate portion, 95 being normally less than the corresponding dimensions of the rail flange, those portions of the rail anchor which are subjected to 100 the greatest bending stresses being provided with integral thickenings.

3. A rail anchor comprising a bent bar, 105 the intermediate portion of which is formed to contact with the lower surface of the rail flange, the end portions being adapted to contact with the upper surfaces of the rail flanges, the distance between the gripping surfaces of the end portions and the bearing surface of the intermediate portion being 110 normally less than the corresponding dimensions of the rail flange, the curved ends and intermediate portions of the rail anchor which are subjected to the greatest 115 bending stresses being provided with integral thickenings.

4. A rail anchor comprising a bar of metal having terminal jaws of unequal lengths, an intermediate portion bent toward 120 said jaws, one or more of the bent portions being stiffened by integral deepening thereof.

5. A rail anchor formed from a single bar of metal bent to form an upwardly bowed body portion and terminal jaws of unequal 125 length, the curved end portions and bowed body portion being stiffened by integral deepening thereof.

6. A rail anchor comprising a bar, the ends of which are bent over toward the body por- 130

tion to form jaws, the intermediate portion being bent toward said jaws, the dimensions being such as to require springing or bending action to place the same in position on 5 the rail flange, the curved end portions and the bent body portions being stiffened by integral deepening thereof.

7. The method of making rail anchors comprising forming a bar with integral 10 deepenings at predetermined locations thereon, then bending said bar to form a pair of clamping jaws, with the deepened portions located at the curved ends thereof.

8. The method of making rail anchors comprising forming a bar with an integral 15 deepening thereon, then bending the ends of

said bar to form a pair of clamping jaws, and bending the body portion, including said deepening, toward the opening between said jaws.

9. The method of making a rail anchor comprising the production of a metal bar, with integral thickenings at predetermined locations thereon, then bending the ends of 20 said bar to form a pair of clamping jaws with the integral thickenings at one or more of the locations subjected to the greatest bending stresses.

In witness whereof I hereunto affix my signature.

EMIL C. DANNER.
